US00D771177S

(12) **United States Design Patent** (10) **Patent No.:** **US D771,177 S**
Sirius-El (45) **Date of Patent:** **** Nov. 8, 2016**

(54) **APPARATUS FOR PROJECTING MEDIA CONTENT ON SMART LENSES**

(71) Applicant: **Yusef Sirius-El**, Miramar, FL (US)

(72) Inventor: **Yusef Sirius-El**, Miramar, FL (US)

(**) Term: **15 Years**

(21) Appl. No.: **29/533,981**

(22) Filed: **Jul. 23, 2015**

(51) LOC (10) Cl. **16-06**

(52) U.S. Cl.

USPC **D16/309**

(58) **Field of Classification Search**

CLAIM

The ornamental design for an apparatus for projecting media content on smart lenses, as shown and described.

DESCRIPTION

FIG. 1 is a front perspective view of the invention.

FIG. 2 is a rear perspective view of the invention.

FIG. 3 is a bottom view of the invention.

FIG. 4 is a top view of the invention.

FIG. 5 is a right side view of the invention.

FIG. 6 is a front plan view of the invention; and,

FIG. 7 is a rear plan view of the invention.

1 Claim, 6 Drawing Sheets
